UNITED STATES PATENT OFFICE

MARTIN A. SISK, OF PITTSBURGH, PENNSYLVANIA

SURFACE DRAIN

Application filed December 20, 1928. Serial No. 337,332.

This invention relates to surface drains, and the primary object is to provide a non-clog drain, that is to say, one which will admit the free flow of liquids therethrough, but which will prevent refuse from entering the main outlet of the drain and obstructing the same. A more specific object is to provide a surface drain which will prevent obstruction of the drain outlet by floating solids or refuse and which will also prevent obstruction of the drain outlet by submerged solids or sediment.

A further object is to provide a simple drain construction affording removable chambers which will receive and retain both floating and submerged refuse in such position as not to obstruct the passage of liquids until such time as the accumulation of refuse renders removal thereof necessary.

Further specific objects include the provision of a simple and effective device for retaining both submerged and floating solids and which will facilitate simultaneous removal of solids of each character mentioned.

Further objects include the provision of a drain in which all floating liquids, such as light oils, gasoline and the like, may be caused to discharge into the main outlet leading to the sewer, while retaining floating and submerged solids.

Another specific object is to provide a floating solids retaining device including a liquids strainer which will act on such solids, while still submerged, to direct them in such manner as not to tend to clog the strainer.

Further objects and features of the invention will become apparent from the following description relating to the accompanying drawings wherein I show the preferred forms of the invention, including various modifications. The essential characteristics are summarized in the claims.

In the drawings, Fig. 1 illustrates a drain

in substantially central vertical cross section and shows a removable sediment receptacle; Fig. 2 is a view similar to Fig. 1, showing a modified form of drain with a fixed sediment chamber, and further showing a modified arrangement of drain outlet.

The general features of the present invention are as follows: There is a hollow drain body open at the top and provided with a grate structure for determining the size of solids which may enter the drain. Beyond this is a liquids and solids conveyor preferably centrally of the drain and communicating with the grate openings, and which carries these liquids and solids toward the bottom of the drain. The conveyor discharges into a sediment chamber located at the bottom of the drain body.

Associated with the sediment chamber is a refuse retention device which may be variously arranged depending on the character of refuse and the manner in which it is desired to retain the same, for example, whether liquids of a particular character or whether solids, and if solids whether these are to be retained above and below the liquids level of the sediment chamber, etc.

A characteristic shown, is the provision of auxiliary inlet openings and an auxiliary inlet chamber below such openings which, in the event that solids accumulate within the drain to such an extent that liquids cannot get through in the usual manner to the main outlet, will permit liquids to be drained off the floor substantially directly into the sewer drain line through the main outlet, by-passing the refuse retainer. This arrangement just discussed also provides venting means to prevent the accumulation of volatile gases, particularly explosive gases, from being trapped and retained in the drain body.

A further general feature of the invention is the arrangement of retainer walls and strainer openings by which buoyant solids

temporarily submerged by agitation of the liquid containing them, are forced in a direction contrary to that which would naturally result in clogging the strainer openings.

With the above general description in view, my invention resides in various arrangements designed to carry out the above objectives and embody the features generally discussed above, as well as other specific features to be later set forth.

Referring again to the drawings, 1 indicates the drain body. This has a shouldered opening at the top designated 2, and a flange 3 adjacent to the opening which overhangs the side walls of the body, outwardly therefrom, and forms a strengthening rib for the top of the body. Below the flange 3 and extending outwardly from the side wall of the body is a flange 4 which may be considerably varied in construction, but which is preferably terraced as at 5, partly to provide securing anchor surfaces for the concrete formation of the floor, but mainly to direct seepage liquid toward the body.

The flanges 3 and 4 cooperate in holding the drain body in position in the floor structure since, in the event that the body of concrete extends no lower than the lowermost surfaces of the flange 4, the drain will be prevented from shifting either up or down, as will be appreciated from inspection of the drawings. Further, the flange 3 reduces chipping of the concrete at the edge of the fitting by reason of overhanging an annulus of concrete therebeneath and strengthening the same.

Associated with the anchor 4 and extending through the body wall, are a suitable number of seepage openings 6 which drain off any liquid which may accumulate about the body below the flange 3, this seepage discharging into the drain body, and thence to a main outlet to be presently described.

The drain body is provided with an outlet hub. The hub 7 is disposed at the bottom of the body. The main discharge opening is indicated at 10.

Referring again to the drawings, 15 is a suitable main inlet closure member in the nature of a grate having enlarged openings 16 therethrough, preferably diverging downwardly to prevent clogging, the outer edges of the grate being seated in the shouldered opening 2, and resting on the shoulder. Below the grate and substantially in intimate contact therewith so as to catch all materials, whether liquids or solids entering the main grate openings 16, is a hollow conveyor member 18 forming a main liquids and solids receiving chamber. This conveyor, as shown, has a downwardly converging wall 19, joining a more restricted extension 20 to discharge liquids and solids centrally of the drain body. The liquids and solids conveyor 25 may comprise an extension thereof to dip be-

low the normal liquids level of the sediment chamber, formed as will be presently shown, to prevent agitation of caught refuse and to provide a water seal. I may, if desired, provide a removable extension 20', engaging and supported by the conveyor member 18.

It is to be understood, of course, that the sediment chamber may be fixed or removable, and is disposed to catch all materials passing through the conveyor. Fig. 2 illustrates a fixed sediment chamber, comprising the bottom 25 and adjacent side walls of the drain body 1 below the liquid level L—L'.

In the drawings there is disclosed a removable sediment chamber, comprising a receptacle 23 in the nature of a bucket, having supporting lugs 24, for resting on the bottom of the drain body. In this and similar instances, the sediment receptacle brim determines a liquids level L' above the general body liquids level L. The sediment receptacle has a suitable number of lugs, preferably four, two of which are arranged to support a bail 27, adapted to lie within the drain body and at one side of the conveyor 18 in easily accessible position.

The refuse retention means, as shown in the drawing, are rigidly associated with and include part of the conveyor. As shown, the lower end of the extension 20 has rigid therewith a downwardly diverging skirt 30. In Fig. 1, this rests on and is supported by a suitable number of inwardly projecting lugs 31, formed on the wall of the sediment receptacle 23. The rigidly combined elements may be removed from the body by the use of a handle, comprising a cross bar 28 positioned in suitable registering openings near the top of the conveyor member 18.

The retainer member 30, in order to hold back substantially all solids while permitting excess liquids to drain from the sediment receptacle through the body to the main channels, shown as small horizontally extending perforations 33 therethrough. The member 30 cooperates with the sediment chamber wall to prevent escape of either submerged or floating solids therebetween. As shown, this cooperation is effected by continuous line contact of the outer edge of the skirt with the sediment chamber wall. In Fig. 2 the skirt has an imperforate horizontal flange 32, substantially continuously engaging the main drain body wall. When it is desired to discharge floating liquids, the openings 33 are disposed at the liquids level L' as at 33' and below this level.

By the arrangement shown, it will be seen that sediment discharged through the conveyor will be deposited at the bottom of the sediment receptacle while floating refuse, temporarily submerged, will be directed upwardly by the inclined wall 30, and in a direction generally contrary to that favoring

a tendency to clog the openings 33, into the imperforate part of the retention means.

It will be noted that the openings, such as 33, comprising the outlet of the retention means, are of individually lesser area than those of the main inlet holes 16. The former are preferably much smaller in size to prevent the escape of very small particles of solids.

10 Suitable means forming a main water seal trap is illustrated. This may be entirely separate from the drain body and may comprise a pipe 35 having an upward bend as at 36, the lowermost interior surface of which determines the liquids level L within the drain body. It is desirable, particularly where a removable sediment receptacle is provided, to have its liquids level above the level L; as shown, for example, so that buoyant liquids 15 discharged through the openings 33 will more readily drain off the top of the receptacle 23, so as not to be removed with the receptacle.

It is manifest that continued use of the drain without cleaning will eventually result in blocking the intended channels by accumulated refuse so that a pool of liquids may be caused to stand above the main inlet to the drain body for a considerable period. This 25 is obviously undesirable. To prevent this, I provide the auxiliary inlet and by-pass discharge, previously mentioned.

The by-passing arrangement, as shown, 30 comprises a suitable number of small openings 17, outwardly from the larger opening 16, preferably downwardly diverging in shape to prevent clogging by solids. Such openings lie outwardly from the top edge of the main inlet chamber, so as to discharge directly into the body without passing through the sediment chamber, the retainer, etc. Thus, assuming the normal passages are clogged, liquid from the surface to be drained will pass through the opening 17, and run 35 directly down into the drain outlet 10. The auxiliary inlet openings are much smaller than the main inlet openings, hence, although they will serve to drain the surface above of liquid so long as this surface is kept clean 40 of refuse, the device acts as a "tell-tale" to inform the attendant when the solids retention means are obstructed, because liquid will run through the openings 17 much more slowly than through the normal channels.

45 The openings 17 have a further function in that they will discharge all volatile gases accumulating within the drain body and likely to stand about the conveyor 18, where they might cause an explosion if ignited when the various parts are removed for cleaning.

The conveyor, previously designated 18, has restricted extension or dip-pipe proper formed at 20', which enters the sediment chamber to a point below the liquids level 50 thereof, making an air seal and causing the

discharge into the sediment chamber to be below the liquids level, thus causing light oils and other buoyant liquids, gasoline for example, to overflow the sediment receptacle. In other words, oil and gasoline remaining 70 from previous discharges at the top of the sediment chamber is immediately washed out and does not become emulsified with the water.

75 The bottom or outlet end of the extension 20' may also extend some distance below the lowermost outlet holes of the retainer, and thus comprise the lowermost portion of the retention means. Thus, submerged solids accumulating within the sediment chamber 80 may reach and obstruct the outlet end of the extension before reaching and obstructing the retainer outlet holes, and preventing formation of a static head of water within the retention means and beyond the extension 85 pipe.

90 The outlet of the extension 20' is preferably of lesser area than that of any of the outlets beyond the extension thereby creating an easy discharge through the drain, preventing undue disturbance of solids held therein, and also preventing undue rise of the liquids level.

95 The retainer member and extension or dip pipe, and incidentally all the tubular bodies of the illustrated constructions, are preferably circular in cross section, but may be of any desired shape, square for example.

100 In the above description, the terms "floating" and "submerged" have been used extensively as modifying solids. It will be understood, however, that in certain instances the parts of the solids retention means function without regard to the character of solids. The terms "floating" and "submerged" as appearing in the claims are, therefore, in general not to be construed as limiting but rather explanatory terms.

I claim:—

110 1. A drain comprising a body having a main inlet to admit liquids and solids, means forming a main inlet chamber within the body and communicating with the main inlet, means forming a sediment chamber beyond the inlet chamber and into which the latter discharges, a main outlet for the drain body disposed beyond the sediment chamber 115 to receive liquids therefrom, and a solids retention means extending downwardly materially below the liquids level of the sediment chamber, said retention means being disposed between the sediment chamber and main outlet and cooperating with the sediment chamber wall to block the exit of both submerged and floating solids from the sediment chamber between the retention means and such chamber wall, the retention means being arranged to allow the passage of liquids from the sediment chamber to the main outlet and 120 125 130

to retain such solids against obstructing the main outlet.

2. A drain according to claim 1, wherein the main inlet includes a member having a plurality of inlet openings, and the retention means includes a hollow body having a wall substantially in continuous line contact with the sediment chamber wall, and providing liquid discharge openings of individually lesser area than the main inlet openings.

3. In a drain, a hollow body having a main inlet, a conveyor for liquids and solids beyond said inlet and communicating therewith, means forming a sediment chamber into which the conveyor discharges, and retention means including a wall member extending substantially from the inner wall of the chamber below the liquids level of the chamber to a point materially above the liquids level of the chamber, arranged to retain both submerged and floating solids from escaping from the drain, said wall being perforate below the liquids level of the chamber to permit liquids to pass from the sediment chamber unobstructed by accumulated floating refuse, and main outlet means to receive such liquids and conduct them from the body.

4. A drain according to claim 3, wherein the perforate portion of the solids retainer wall inclines toward the vertical axis of the sediment chamber and upwardly to divert the floating solids in a direction away from the perforations, as these solids rise to the liquids level of the sediment chamber.

5. Apparatus according to claim 3, wherein in the retention means is tubular and has a plurality of openings therethrough for conducting liquid from the sediment chamber outwardly to the main outlet, the openings providing substantially horizontally extending relatively small channels, and the retention means converging upwardly to deflect buoyant solids away from such channels.

6. In a drain, a drain body having a main inlet, tubular conveying means below said inlet and communicating therewith, means forming a sediment chamber below said conveying means, and a tubular solids retention member cooperating with the sediment chamber wall and the wall of the conveying means to substantially block all exit of solids from the drain while affording exit for liquids, said member forming within itself a substantially continuous retaining space for floating solids.

7. A drain comprising a body having a main inlet for liquids and solids, means forming a main inlet chamber within the body and communicating with said inlet, means forming a sediment chamber beyond the inlet chamber and into which the latter discharges, a main outlet for the drain body disposed beyond the sediment chamber to receive liquids therefrom, there being an extension pipe communicating with the inlet chamber and dis-

posed with its discharge end below the brim of the sediment chamber to effect an air seal therewith, and tubular means disposed outwardly from said extension and cooperating with the extension to form a floating solids retaining space.

8. In a drain, a hollow body having a removable perforate top closure, tubular means communicating with the perforations and extending downwardly into the body, means forming a sediment chamber including means associated with the chamber to maintain a constant liquids level above the discharge end of the tubular means to form a water seal therewith, and means including a continuous partially submerged wall arranged about and in generally spaced relation to said discharge end of the tubular means and substantially in line contact with the entire side wall of the sediment chamber, said last named means being arranged to provide openings for discharging liquids while retaining both submerged and floating solids against exit from the drain body, and means affording an outlet for said body.

9. In a drain, a body having a perforate top closure, a sediment receptacle beyond the closure and means to maintain a constant liquids level for said receptacle, means to direct liquids and solids from the closure toward the receptacle, means at least partially submerged in the sediment receptacle and lying outwardly from the lowermost portion of the directing means, and including a wall having perforations therethrough individually smaller than the perforations of the closure for retaining both submerged and floating refuse discharged toward the receptacle by the directing means, against exit from the body, while affording passage for liquids, and a main outlet for the body for receiving such liquids.

10. A surface drain according to claim 9, wherein said perforate wall of the solids retainer has the perforations thereof disposed at and below the liquids level to discharge buoyant liquids from the receptacle, and said wall has a substantially imperforate tubular body portion above the liquids level.

11. In a drain, a body having a perforate top closure, tubular conveyor means below the closure communicating with the perforations thereof, a sediment receptacle below the conveyor, and means to maintain a constant liquids level for said receptacle, solids retention means partially submerged in the sediment receptacle and extending above the liquids level, said retention means being disposed outwardly from the tubular means, and including a wall having perforations therethrough, said wall extending above and below the liquids level for retaining both submerged and floating solids, discharged toward the receptacle through the tubular means, against

- exit from the body, while affording drainage for liquids.
12. A retaining device for drains, comprising means to maintain a normal liquids level in the drain body, and a tubular member extending above and below such level and having an upwardly converging portion below such level with substantially horizontally extending openings therethrough.
13. A retaining device for drains, comprising means to maintain a normal liquids level in the drain body, and a substantially continuous floating and submerged solids retainer wall within the body having an inclined portion extending below such level with strainer openings therethrough below such level, whereby floatable solids buoyed upwardly along the inclined portions are given a tendency to clear rather than clog the openings.
14. A drain comprising, a body having a main inlet to admit liquids and solids, means affording a main outlet, conduit means interposed between said inlet and outlet arranged to retain solids from passing to said outlet while passing liquids thereto, and an auxiliary inlet for liquids arranged to by-pass the conduit means and pass said liquids directly to the drain outlet in the event the conduit means becomes clogged by accumulated refuse.
15. A drain according to claim 14, wherein both inlets comprise means providing a plurality of openings near the surface to be drained and the auxiliary openings are of individually lesser area than the main inlet openings.
16. A drain comprising, a body having a main inlet member arranged to admit liquids and solids, tubular means forming a main inlet chamber within the body and communicating with the main inlet, a sediment chamber within the body, and solids retaining means associated therewith arranged for holding submerged and floating solids in the vicinity of the sediment chamber, a main outlet for the body to receive and drain excess liquids from the sediment chamber, and an auxiliary liquids inlet associated with the main inlet member and including means having an inlet opening communicating with the surface above the drain body and directly with the interior of the body between the wall thereof and the main inlet chamber, for by-passing the main flow directly into the main outlet through the body in the event either the inlet chamber or sediment chamber become blocked by accumulation of refuse.
17. In a drain, a hollow body having a main inlet to admit liquids and solids, means forming a main inlet chamber within the body and communicating with the main inlet, means forming a sediment chamber below the inlet chamber and into which the latter discharges, a retaining means arranged about the main inlet chamber and extending into substantially continuous line contact with the sediment chamber wall including strainer means for permitting the exit of liquids from the sediment chamber while holding back both submerged and floating refuse, there being a dip pipe disposed as a continuation of the inlet chamber, said pipe discharging materially below the liquids level of the sediment chamber to form an air seal therewith and to prevent agitation of retained floating refuse by precipitate charging of the drain.
18. Apparatus according to claim 17, wherein the dip pipe portion of the apparatus is removably disposed in the main inlet chamber forming means.
19. In apparatus of the character described, a drain body having a main inlet, and an outlet arranged to maintain a liquids level above the bottom of the body, conveying means communicating with said inlet, means forming a sediment chamber disposed at the discharge end of said conveying means and arranged to maintain a liquids level above the aforesaid liquids level, and a retainer arranged to prevent exit of solids from the vicinity of the sediment chamber while discharging both light and heavy liquids substantially at such higher liquids level.
20. A drain comprising a body having a main inlet, means forming a main inlet chamber within the body and communicating with the inlet, said chamber having a restricted discharge extension, means forming a sediment chamber in the body, and means affording a liquids level therefor materially above the discharge end of the said extension, a solids retaining means interposed between said extension and the sediment chamber for holding floating refuse in the vicinity of the sediment chamber, said retaining means providing a liquids outlet therefrom, and a main outlet for the body to receive and drain excess liquids from the sediment chamber, the discharge area of said extension being less than the area of either the said liquids outlet from said retaining means or said main outlet.
21. In a drain, a body having a main inlet for liquids and solids and a main outlet, a removable receptacle disposed within the body and adapted to be removed from the drain, there being means to convey such liquids and solids to the receptacle, and a solids retention means within the body and engaging the receptacle and cooperating therewith to block the passage of solids to the main outlet while passing liquids thereto.
22. In a drain, a hollow body having a main inlet and a main outlet, tubular retention means communicating with the main inlet and the main outlet, means forming a solids chamber arranged to receive discharge from the main inlet and affording a normal liquids level in said chamber, the retention means extending downward materially below

the liquids level of the solids chamber and cooperating with the solids chamber to block the exit of solids from the solids chamber, the retention means being also arranged to allow passage of liquids from the solids chamber to the main outlet.

23. A drain according to claim 22 wherein the solids chamber comprises a sediment receptacle removable from the drain body.

10 In testimony whereof, I hereunto affix my signature.

MARTIN A. SISK.

the liquids level of the solids chamber and cooperating with the solids chamber to block the exit of solids from the solids chamber, the retention means being also arranged to allow passage of liquids from the solids chamber to the main outlet.

23. A drain according to claim 22 wherein the solids chamber comprises a sediment receptacle removable from the drain body.

10 In testimony whereof, I hereunto affix my signature.
